ATTORNEYS

UNITED STATES PATENT OFFICE.

WILLIAM L. DEMING, OF SALEM, OHIO.

NOZZLE.

Original application filed August 25, 1919, Serial No. 319,718. Divided and this application filed July 5, 1921. Serial No. 482,349.

To all whom it may concern:

Be it known that I, WILLIAM L. DEMING, a citizen of the United States of America, residing at Salem, in the county of Columbiana and State of Ohio, have invented a certain new and useful Improvement in Nozzles, of which the following is a full, clear, and exact description, reference being had to the accompanying drawings.

10 This invention relates to spraying apparatus and is primarily concerned with the provision of a nozzle which is adapted for use in any apparatus wherein it is desirable to effect a closure at the fluid discharge point.

One of the objects of my invention is the provision of a simple and cheap nozzle which may be readily installed in existing bathing apparatus, and be utilized therein 20 for controlling the volume of fluid passing therethrough, without changing the mixture at the faucet. Another object is the provision of a nozzle wherein the fluid is discharged through tangential orifices where- 25 by a whirling spray is effected at the point of fluid discharge.

The means for accomplishing the above objects will be fully set forth in the following description, which relates to the 30 drawings, and the essential characteristics of my invention are set forth in the claims.

In the drawings, Fig. 1 is an elevation of a bathing apparatus embodying features of my invention, Fig. 2 is an enlarged sectional view taken through the nozzle and showing the relation of the various members when the nozzle is in "closed" position. Fig. 3 is a similar view showing the relation of the parts when the nozzle is in "open" position; Fig. 4 is a horizontal section showing the tangential discharge orifices in the spray head.

My invention is illustrated in the drawings as embodied in connection with a bathing apparatus wherein 10 indicates a control valve or faucet, 11 a flexible conduit, 12 a nozzle support and 13 a discharge conduit. The nozzle is shown as suspended from an inclined bracket 14 which is attached to a wall 15, and the support itself is shown as a swivelled member for enabling the operator to swing the nozzle, for deflecting the water to any part of the body. The supporting mechanism shown in Fig.

1 forms a part of my copending application, Serial No. 319,718, filed August 25, 1919, and reference may be had thereto for a more thorough description together with the claims covering the subject matter. This application is a division of the above copending application and is concerned with the nozzle attached to the discharge conduit 13.

In Figs. 2 and 3, I have shown the conduit 13 as having a chambered head 20 rigidly secured to the lowermost end thereof, and I have shown such head as having inclined tangential orifices 21, which serve as discharge passageways for all of the water flowing through the conduit. The 70 outer surface of this head is threaded, as at 22, and is arranged to be engaged by the internally threaded casing 23.

The casing is shown as a bell-shaped member having a neck 24 which closely embraces the discharge conduit and which is provided with a stuffing-box 25. The stuffing box 25, comprising a packing ring 26 and a gland follower 27, forms a barrier against the passage of fluid between the casing and conduit, and at the same time provides effective contact surface against the conduit for preventing the casing from rotating about the head 20. The lower portion of the casing is recessed, as at 28, to provide a shoulder 29 and an internally threaded portion, which portion is larger in diameter than the recess occupied by the head 20. The lowermost portion of the outer surface, as at 30, is preferably knurled 90 to provide a convenient grip for turning the casing relatively to the head 20.

Extending across the recessed portion 28 I provide a cap 31 which is threaded externally to engage the lower threads in the casing, and which is preferably equipped with a single central discharge aperture 32. Intermediate the cap and shoulder 29 I provide a gasket 33 which is arranged to be held in close fitting engagement between the cap and casing. The inner edge of the gasket is beveled as at 34 and is so positioned that the tangential discharge orifices 21 will be closed when the gasket is brought into contact with the head. In positioning the gasket, the cap is drawn tightly into engagement with the casing and is thereafter maintained in such position, so that when-

ever the casing is rotated about the head, the gasket is caused to move either into or out of engagement therewith.

In Fig. 2 I have shown the gasket in engagement with the head 20 and consequently as effecting a closure for the orifices 21. When the parts are in this position the water will be prevented from discharging through the vent 32. Should any fluid be forced upwardly between the casing and head, then the stuffing box 25 would prevent the passage of fluid between the conduit and the casing. A further use for the stuffing box is that the casing, when once turned, is maintained in such position by reason of the pressure exerted by the packing ring 26 against the wall of the discharge conduit.

In Figure 3 I have shown a gasket 33 as out of engagement with the chambered head, and consequently as removed from the orifices 21. In this position, the fluid is free to pass into the bowl of the cap and thence out of the discharge passage 32. The arrangement of the orifices 21 causes a whirling discharge which throws the water in a conical spray through the port 32 and thereby provides an effective cleansing action.

The operation of my device is as follows: Assuming that the nozzle is employed in a bathing apparatus and that the temperature of the fluid is regulated by the faucet 10, then the volume of fluid may be controlled by manually turning the nozzle casing 23 on the threaded head 20 whereby the distance between the gasket 33 and the discharge orifices 21 may be controlled at will. In regulating the volume of fluid passing through the nozzle it is obvious that such regulation may be attained without disturbing the temperature control as determined by the faucet 10.

From the foregoing description it will be seen that I have provided a nozzle which may be employed in connection with a bathing apparatus or with any form of spraying device for controlling the volume of fluid to be discharged without in any way affecting the temperature as regulated at another point in the line. Furthermore, it will be seen that I have provided a nozzle which is quite simple in construction and which may be readily attached to existing shower apparatus.

Having thus described my invention, I claim:

1. The combination with a discharge conduit having an enlarged head at one end thereof, the end of said head being dome-shaped and having tangential passageways through the dome-shaped portion, of a casing having two recessed portions, one of said recesses surrounding the head, a cap fitting into the other of said recesses and having a central discharge passageway, a gasket spaced from the head and positioned between the cap and casing and having an annular exposed face disposed within the path of said passageways, said face being complementary to the dome-shaped portion of the head whereby movement of the casing relatively to the head effects a gradual closing of the passageways by the gasket.

2. In a device of the character described, the combination with a conduit having the end thereof terminating in a dome shaped chamber, tangential passageways leading outwardly from said chamber through the dome-shaped portion thereof, a casing surrounding the chamber and out of contact with the passageways and a beveled closure member rigidly secured to the casing and adapted to be brought into engagement with the chamber for closing said passageways, said beveled member being substantially complementary to the dome shaped portion of the chamber.

3. In a device of the character described, the combination with a fluid conduit, of a chambered dome-shaped head secured to the end thereof, tangential inclined passageways extending from the interior to the exterior and adjacent the base of the dome, the exterior portion of the head being threaded, a casing having two concentric internally threaded recesses therein, the inner recess being in engagement with the threaded portion of the head, a cap threaded to the outer recess, said cap having a central discharge passageway therein, a gasket intermediate the cap and casing, said gasket having a portion thereof complementary to the dome-shaped head and comprising a closure for said passageways when brought into engagement with the head.

In testimony whereof, I hereunto affix my signature.

WILLIAM L. DEMING.
